UNITED STATES PATENT OFFICE.

DANIEL BIGGS, OF DENTON, TEXAS.

WASHING-MACHINE.

SPECIFICATION forming part of Letters Patent No. 644,791, dated March 6, 1900.

Application filed August 10, 1899. Serial No. 726,817. (No model.)

To all whom it may concern:

Be it known that I, DANIEL BIGGS, a citizen of the United States, residing at Denton, in the county of Denton and State of Texas, have invented a new and useful Washing Machine, of which the following is a specification.

My invention relates to washing-machines, and particularly to that class in which the clothes are passed through a series of rollers which quickly press the dirt and water therefrom.

The object of my invention is to provide a machine of this class that will quickly and thoroughly cleanse the article of clothing without injuring the fabric or tearing off buttons, that will fit any size tub desired, and one that is simple in construction, being made in few parts, and is comparatively inexpensive.

My invention further consists in the parts and combination thereof hereinafter set forth and claimed.

In the drawings which form a part of this specification, Figure 1 is a perspective view of a washing-machine constructed in accordance with my invention. Fig. 2 is a top plan view of the same with the top bar broken away. Fig. 3 is a vertical transverse section. Fig. 4 is a vertical longitudinal section. Fig. 5 is a view of one of the swinging roller-frames detached. Fig. 6 is a detail perspective view of the corrugated roller.

In the drawings the numeral 1 designates a framework which is composed of the uprights 2, horizontal base-pieces 3, lower cross-bars 4, and upper cross-bar 5.

Journalized on the cross-bars 4 are two swinging roller-frames 6. These frames each comprise two upright standards 7, pivoted to each bar 4 at its opposite ends and just inside the base-pieces 3. This is preferably accomplished by having the ends of the cross-bars 4 made smaller and round, as at 8, forming a bearing which passes through the standard 7 and is fastened securely to the base-piece 3. The upper end of each pair of standards is connected by a cross-bar 9, which holds the same the proper distance apart. The top of each standard is perforated, as at 10, at right angles to the cross-bar 9, and through the perforations of the two opposite standards are

loosely passed the rods 11. The rods 11 have arranged around them the coil-springs 12, which bear against the outer ends of the standards and force them toward each other. To regulate the tension of the springs 12, the ends of the rods 11 are screw-threaded, and adjusting-nuts, which bear against the outer ends of the springs, are screwed thereon; so that the springs may be compressed to any desired tension.

Journalized in the uprights 2, above the level of the tub, is the horizontal corrugated roller 13, which is provided at one end with a handle 14. This roller is provided with longitudinal ribs 15, which extend only part of its length, and is provided with plain ends of less diameter than the corrugated portions, as at 16. Journalized in the standards 7, on either side of the central corrugated roller 13 and on a level with the same, are the horizontal rollers 17, which are held in yielding contact with the corrugated roller 13 by the springs 12.

For fastening my machine to the tub I have provided the horizontal fastening-frame, which consists of the supporting-bars 18 and 19, securely fastened to the uprights 2 at right angles thereto and whose ends project well beyond the vertical planes of the standards 7. Connecting the opposite ends of the bars 18 and 19 are the cross-bars 20, which are pivotally connected to the bar 18 by the hooks 21. The hooks 21 engage around the bottom flange of the tub or like receptacle 85 and have long shanks which pass through perforations in the bars 18 and 20 and are screw-threaded to receive nuts which are placed thereon and are adapted to draw the hooks tightly in engagement with the bottom flange, and thereby securely hold the machine in place. To allow the machine to be applied to different-sized tubs, the bar 19 has each end cut away, as at 22, forming notches in which the ends of the bars 20 may slide and rest. These ends are provided with slots 23, through which hooks 24, similar to the hooks 21 and used in like manner, pass.

In applying my washing-machine to a tub or like receptacle the supporting-bar 18 is placed upon the top edge, the hooks 21 are engaged under the lower flange, and the nuts screwed down tightly upon the top of the bars 20. The opposite ends of the bars 20 are then

adjusted into proper relation to the adjacent bar 19, and the hooks 24 are moved in the slots 23 until they engage under the lower flange of the tub; when the nuts being screwed tightly 5 down upon the bars 20 the machine is securely fastened to the tub.

To operate the machine, the tub being nearly full of water, the clothes are passed around the central roller 13 between the plain 10 rollers 17, as shown in Fig. 2, and are run back and forth through these rollers, which each time press the water and dirt therefrom and quickly cleanse the same. The pressure of the rollers 17 against the corrugated roller 15 13 may be regulated by the adjusting-nuts on the rods 11. Whenever an article of clothing having a row of buttons is washed, by arranging the buttons so that they will pass through the machine at the reduced ends 16 20 of the corrugated roller they will not be broken or torn off, there being no pressure between the rollers at that point.

The cross-bar 5 is so arranged that a wringer may be placed thereon, and being arranged centrally over the tub the water will run directly back into the same and not over the sides, as is the case where the wringer is arranged at the side of the tub.

It will thus be seen that I have constructed 30 a simple, efficient, and comparatively inexpensive washing-machine that will thoroughly and rapidly cleanse the clothes, that will fit different-sized tubs, that will not break or tear off the buttons from the articles of clothing, and that will receive a wringer in a position where it cannot drain outside the tub.

I do not desire to be limited to the exact construction shown in the drawings, as changes in the form, proportion, size, and the minor

details of construction within the scope of 40 the appended claims may be resorted to without departing from the principle or sacrificing any of the advantages of this invention.

Having now fully described my invention, what I claim as new, and desire to secure by 45 Letters Patent, is—

1. In a washing-machine, the combination with the machine-frame carrying washing devices, of a fastening-frame comprising supporting-bars adapted to rest on the top of a 50 tub or like receptacle, cross-bars connected at one end to one of the supporting-bars and adjustable on the other supporting-bar, and hooks connected adjustably to the cross-bars, and adapted to engage under the tub, substantially 55 as described.

2. In a washing-machine, the combination with the main frame-carrying washing devices, of a fastening-frame comprising supporting-bars adapted to rest on the top edge 60 of a tub or like receptacle, cross-bars resting across the opposite ends of the supporting-bars and having slots at one end, hooks adapted to engage the lower flange of the tub and pivotally connecting the ends of the supporting-bar and cross-bars, and similar hooks passing through the slots of the cross-bars and adapted to engage the lower flange of the tub at the opposite sides thereof, substantially as 65 described.

In testimony that I claim the foregoing as my own I have hereto affixed my signature in the presence of two witnesses.

DANIEL BIGGS.
